UNITED STATES PATENT OFFICE.

JOSEPH NAPOLEON LAPRES, OF MONTREAL, QUEBEC, CANADA.

AWNING REFLECTOR-SCREEN.

No. 901,715.

Specification of Letters Patent.

Patented Oct. 20, 1908.

Application filed September 13, 1907. Serial No. 392,653.

To all whom it may concern:

Be it known that I, JOSEPH NAPOLEON LAPRES, a subject of the King of Great Britain, residing in the city and district of Montreal, in the Province of Quebec, Canada, have invented certain new and useful Improvements in Awning Reflector-Screens; and I do hereby declare that the following is a full, clear, and exact description of the invention, such as will enable others skilled in the art to which it appertains to make and use the same.

The invention to be hereinafter described relates to window blinds and screens of a generally similar character and it is particularly adapted to reflect or deflect the maximum of light into a room which would otherwise be poorly lighted.

The main objects of the invention are to provide a blind of this general character which may be positioned at any desired angle and one which will at the same time allow free circulation of air and admit the maximum amount of light. In many instances it is desirable to adjust a plurality of such blinds equally and simultaneously and to that end suitable means have been provided.

A further object of the invention is to provide means for securely locking the several separate parts of the blind or screen in their adjusted positions.

Other objects will be pointed out in the specification and claims hereinafter.

Broadly speaking the invention comprises one or more movable elements adapted to act as blinds or panels each mounted for individual movement, devices for moving these panels to the desired position and means for locking them in such position.

In order that one skilled in the art to which the invention relates may the more readily understand the mode of its application, its construction and operation reference should be had to the accompanying drawings forming part of the present application in which similar reference characters designate like parts throughout the several views.

In the drawings: Figure 1 is a perspective of the device as applied to a plurality of adjoining windows. Fig. 2 is a front view of the device as applied to a single window. Fig. 3 is a side view of Fig. 2. Fig. 4 is a detail of the locking device. Fig. 5 is a detail of a modified form of locking device.

Fig. 6 is a detail of the loose connection between the panels and their supporting rod shown in Fig. 3.

The device as a whole comprises a plurality of panels 1. In the preferred form of the device these panels consist of suitable open frameworks of rods of suitable material and of the desired size to which are attached canvas, duck or similar light colored material. These panels are mounted to have individual rotary movement in suitable brackets or about suitable supporting rods. When mounted to swing horizontally as in Fig. 1 the preferred form of connections between panels 1 and the supporting brackets will comprise pins or projections 2 on the framework of the respective panels and screw eyes 3 passing through brackets and adapted to freely receive such pins or projections.

In order to lock each panel in its adjusted position a plate 4 provided with perforations 5 is secured to the support of each of the panels 1 adjacent to one of the projections 2. Preferably this plate is semicircular in shape and is placed so that the projection 2 is in line with the centers of its diameters. A pin 6 depending from the lower edge of the framework of the panel is adapted to selectively engage the perforations 5 of the plate and so prevent rotation of the panel after it has been adjusted as desired.

For operating the device a cord, cable or similar flexible connection 7 passing over a pulley 8 is used. This operating device is loosely attached in any suitable way to the free edge of each panel so that by pulling on the cord all of the panels connected thereto may be similarly and simultaneously operated. By slipping the connection between any one of the panels and the operating device such panel may be operated individually.

When adapted for use on a single large window or opening the device is mounted to permit both swinging movement of the panels individually and bodily sliding movement of them relatively to their support. For this latter purpose the projections 2 are bent into eyes which engage rings 10 mounted to travel freely on supporting rods 11 secured at the opposite sides of the window. To these eyes 10 are secured cords, cables or similar flexible connections 12 which pass over pulleys 13.

When the device is adapted for use on a single large window, as above set forth, the panels swing vertically from their supports and travel bodily along the supports in a vertical direction. In traveling bodily along their supports, the panels are limited in their movement, as will be obvious. Consequently, when the uppermost panel reaches the upper end of its support, the succeeding panels will successively approach it and the whole device will be compactly folded together. The same is true of course when the panels travel in the opposite direction. To afford this telescopic construction, where-by the several panels may approach one another, flexible connections 14 and 15 are secured respectively to the loose ring 10 and to the outer edge of the lower panel. These connections, of course, may be passed over suitable pulleys and arranged to be grasped together, so that by pulling on both simultaneously and equally, the panel to which they are attached will be raised, while at the same time the angle to which it has been previously set will be substantially maintained.

When the several panels have been drawn upward together by the connections 14 and 15 into a compact bundle, the whole device may be swung upward against the building to which the device is applied by simply fastening the connections 12 and 14 and pulling on the connections 7 and 15. Likewise, to fold the device adjacent the lower end of the window, it is simply necessary to loosen all connections 7, 12, 14 and 15, when the several panels will fall by gravity, and, due to the loose connections between the panels 1, rings 10 and rods 11, will telescope toward one another and fold in a compact bundle against the building to which the screen is attached.

This device is peculiarly adapted for lighting rooms by reflection. The several panels comprising the whole are adapted to be so adjusted relatively to one another and to the window or opening on which they are used, as to intercept and reflect the sunlight into the room or apartment to be lighted, without allowing the sun to shine directly into the room.

The device as constructed in its preferred form is also adapted to act as a screen or blind for substantially excluding light from a room or building. This is accomplished by mounting the several panels so close to one another that when folded toward the window or opening on which they are used, they will, in their extreme position, present

a substantially continuous wall, intercepting 60 and reflecting away from the opening the sunlight which would otherwise enter.

It is obvious that many changes may be made in the particular way in which the individual panels are mounted, the constructions of the several panels, the devices for operating them, and many other changes and alterations in the construction of the several parts and their combinations, without in any way departing from the scope and extent of 70 this invention, and it is meant to include all such in the present application.

Having thus fully described my invention, what I claim as new, and desire to secure by Letters Patent, is:—

1. A series of fabric-covered panels, individually journaled for limited rotary movement, in combination with means for locking each panel independently in any one of several angular positions and a cord connected 80 to all of said panels and adapted to operate them simultaneously substantially as set forth.

2. A series of panels each of which is mounted to turn through a part of a circle 85 and is permitted a limited up and down motion bodily, in combination with flexible means for operating all the panels together, each panel being adapted to be readily freed from said means and moved independently 90 endwise, or from one pivotal position to another and means for locking each panel in any one of several pivotal positions substantially as set forth.

3. A series of pivotally adjustable panels, 95 in combination with a cord connected detachably thereto in order that all of said panels may be operated together, or each one of them independently on disconnecting it from said cord and locking devices for holding 100 each panel in any one of several pivotal positions substantially as set forth.

4. A series of pivotally adjustable panels, in combination with means, detachable from each panel, for operating all of said panels 105 together, and fixed plates provided with series of perforations and arranged in proximity to said panels, each panel being provided with a part adapted to fit into any one of the holes of one of said plates for locking each 110 panel in any one of several pivotal positions substantially as set forth.

In witness whereof I have hereunto set my hand in the presence of two witnesses.

JOSEPH NAPOLEON LAPRÉS.
